UNITED STATES PATENT OFFICE.

WILLIAM A. MURRAY AND CHARLES E. PUTNAM, OF CHISHOLM, MAINE.

FOURDRINIER MACHINE.

1,280,524.

Specification of Letters Patent.

Patented Oct. 1, 1918.

Application filed May 14, 1918. Serial No. 234,544.

To all whom it may concern:

Be it known that we, WILLIAM A. MURRAY and CHARLES E. PUTNAM, citizens of the United States, residing at Chisholm, in the county of Franklin and State of Maine, have invented certain new and useful Improvements in Fourdrinier Machines, of which the following is a specification, reference being had to the accompanying drawings.

10 This invention relates to Fourdrinier machines, and has for its primary object to provide improved means of a very simple character, whereby undue wear upon the wire cloth which carries the paper pulp as it moves over the suction boxes will be obviated, and the life of the cloth materially prolonged.

20 It is a more particular object of the invention to provide an improved mounting of the suction boxes and means for imparting a reciprocatory movement to the boxes as a unit in the direction of movement of the wire.

25 It is likewise one of the detail objects of the invention to provide a reciprocatory bar mounted upon each side of the Fourdrinier frame and anti-friction means interposed between the frame and said bar, each of the 30 suction boxes being provided with an upwardly and inwardly extending arm fixed to said bar and an actuating piston operatively connected to the forward end of each of said bars.

35 It is also a further general object of our invention to provide improvements in Fourdrinier machines of the character above specified which are simple and inexpensive in construction, reliable and efficient in practical operation, and which will result in material economy in the maintenance cost of such 40 machines.

45 With the above and other objects in view, the invention consists in the improved combination, construction and relative arrangement of the several parts as will be herein-after more fully described, subsequently claimed and illustrated in the accompanying drawings, in which similar reference 50 characters designate corresponding parts throughout the several views, and wherein:

55 Figure 1 is a plan view of a part of a Fourdrinier machine to which one embodiment of our invention is applied;

Fig. 2 is a side elevation;

Fig. 3 is a section taken on the line 3—3 of Fig. 1;

Fig. 4 is a section taken on the line 4—4 of Fig. 1; and

Fig. 5 is a section taken on the line 5—5 of Fig. 1.

In the operation of Fourdrinier paper making machines, the longitudinal movement of the wire cloth which carries the paper pulp over and upon the suction boxes results in the wearing of grooves in the top walls of the boxes, and also in excessive wear upon the wire cloth so that the latter has a relatively short life and has to be frequently renewed. The average wire employed in such machines remains in service for only about ten days. As is well known in the art, this wire is rapidly vibrated during its longitudinal movement over the suction boxes, and it has heretofore been proposed to reciprocate the suction boxes transversely with respect to the line of movement of the wire cloth so that the wire will not have continuous frictional contact at one place upon the suction boxes, whereby the wearing of grooves in the box walls as above referred to will be obviated. While such a device is more or less effective for this particular purpose, it does not prevent wear upon the wire nor appreciably increase the lift thereof. It is, therefore, the primary object of our present invention to provide a mechanism which will not only prevent the wearing of grooves in the suction box walls, but which will also minimize wear upon the wire by reason of its contact with the suction boxes and materially prolong the period of serviceability of the latter.

To the above end, we provide at the ends 95 of each suction box 5 the castings or extensions 6 having the inwardly projecting longitudinally extending arms 7 spaced above the top wall of the suction box. 8 designates the side bars or rails of the Fourdrinier frame. Upon these side rails the bars 9 are mounted for longitudinal reciprocatory movement. The arms 7 extend transversely upon the bars 9 and are detachably secured thereto by means of screws 9', as 100 clearly seen in Fig. 1 of the drawings. The bar 9 is provided in its bottom face and immediately above each suction box with a longitudinally extending groove to receive an anti-friction bearing roller 10, which has 105 free rolling contact upon the upper surface of the frame rail 8. The rail 8 is further

provided with spaced longitudinally elongated openings 11 therein to receive the pins 12 fixed in the bar 9 and this bar is provided at each of its ends with an elongated 5 opening 13 to receive a guide pin 14 which is fixed in the rail 8.

C designates the wire cloth which moves longitudinally between the side rails 8 of the machine frame and over the perforated 10 top walls of the suction boxes 5. As hereinbefore noted this wire cloth is caused to vibrate vertically, so that it has intermittent sliding contact upon the top walls of the suction boxes. The theoretical fulcrum 15 for the vibrating wire cloth is the feed roller arranged at the forward or entering end of the machine.

The forward end of each bar 9 is formed with an angular arm 15 extending downwardly at the outer side of the rail 8. In 20 the lower end of this arm a reciprocating piston rod 16 is engaged to impart a longitudinal reciprocating movement to said bar, and consequently to the series of suction 25 boxes which are mounted thereon. The actuating pistons for the bars 9 may be operated by air, steam or water, or, in lieu of such pistons any desired means for imparting such a reciprocatory movement to the 30 suction boxes may be employed. Therefore, as the specific or detail construction of the actuating means constitutes no part of the present invention it will not be herein further described in detail.

35 From the foregoing description taken in connection with the accompanying drawings, the construction and manner of operation, together with the several advantages of our invention will be clearly and fully understood. As the pulp carrying wire moves 40 over the suction boxes, and in such movement is vertically vibrated, the suction boxes are simultaneously moved as a unit and rapidly reciprocated in the direction of movement of the wire. By thus reciprocating the suction 45 boxes in a longitudinal direction, there is an appreciable decrease in the time during which the wire has sliding frictional contact upon the box walls, and wear upon the wire 50 will thus be greatly reduced. It has been found in practice that by means of our invention, instead of having to renew the wire every ten days, the wire cloth will remain serviceable for a period of seventeen days. 55 It will, therefore, be appreciated that considerable economy will be realized in the cost of operation and maintenance of the machine. This is particularly true under 60 present industrial conditions as the cost of the wire is very high. The use of our improvement necessitates no alterations of a material character in the suction boxes or the other parts of the Fourdrinier machine and may be operatively applied to the 65 machine at comparatively small cost. We have

herein referred to a particular mounting of the suction boxes whereby they may be reciprocated, but it is to be understood that other means than that herein referred to may be adopted for the mounting of these boxes. 70

Another advantage incident to the present invention, resides in the fact that it is only necessary to plane the covers or tops of the suction boxes when a new wire is put on. In the use of such machines at the present 75 time, the wear of the wire upon the suction box covers is so great that these covers must be planed every day. The suction boxes may be independently detached from the bars 9 by removing the screws 9', so that two 80 boxes may remain in operation while the other is being planed or repaired.

It will, of course, be apparent that, if desired, the operating means for the suction boxes may be applied to only one side of the 85 machine instead of to both sides thereof, as illustrated in the drawings.

While, therefore, we have herein shown and described the preferred construction and relative arrangement of the various 90 parts of the device, the same is nevertheless susceptible of many minor modifications and we, therefore, reserve the privilege of adopting all such legitimate changes as may be fairly embodied within the spirit and scope 95 of the invention as claimed.

We claim:—

1. In a Fourdrinier machine, a plurality of suction boxes, and means having a fixed connection with the suction boxes for imparting a unitary reciprocating movement to all of said boxes at the same time in the direction of movement of the paper making wire. 100

2. In a Fourdrinier machine, a plurality of suction boxes, bars mounted upon the frame of the machine to reciprocate in the direction of movement of the paper making wire, means for suspending the suction boxes at their ends from the respective bars, and 105 means for reciprocating said bars. 110

3. In a Fourdrinier machine, a plurality of suction boxes, means for suspending the suction boxes from the side bars of the machine frame, and means fixed to said suspending means for reciprocating all of said boxes at the same time in the direction of movement of the paper making wire. 115

4. In a Fourdrinier machine, a plurality of suction boxes extending at their ends beneath the side rails of the machine frame, bars mounted upon said rails for reciprocatory movement in the line of movement of the paper making wire, means for suspending the suction boxes at their ends from said 120 bars, and means for reciprocating said bars. 125

5. In a Fourdrinier machine, a plurality of spaced suction boxes extending transversely of the machine and beneath the side rails of the machine frame, bars mounted 130

upon said rails to reciprocate in the line of movement of the paper making wire, castings on the opposite ends of each box having inwardly projecting arms fixed to the 5 respective reciprocating bars, and means connected to said bars at one of their ends for reciprocating the same.

In testimony whereof we hereunto affix

our signatures in the presence of two witnesses.
